CLAIM

The ornamental design for a lamp, as shown and described.

DESCRIPTION

FIG. 1 is a front, right side, top perspective view of a lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of that portion of the lamp which is illustrated within the encircled area 8 within FIG. 2. The broken lines depict portions of the lamp that form no part of the claimed design.
